UNITED STATES PATENT OFFICE

2,598,326

NEGATIVE FEEDBACK AMPLIFIER

Eric Lawrence Casling White, Iver, and Edward Arthur Newman, London, England, assignors to Electric & Musical Industries Limited, Hayes, England, a British company

Application November 18, 1947, Serial No. 786,748
In Great Britain November 20, 1946

7 Claims. (Cl. 179—171)

1

This invention relates to amplifier circuit arrangements and has for its object to provide an improved negative feedback amplifier with a view mainly to obtaining a low output impedance, or in some cases a high output impedance with the employment of fewer valves than hitherto necessary by using electron multiplier valves.

The expression "electron multiplier valve" used herein and in the claims is intended to mean an electron discharge valve which comprises a thermionic cathode which can be caused to emit primary electrons, a control electrode, at least one secondary electron-emitting electrode (hereinafter and in the claims referred to as a dynode) on to which said primary electrons can be caused to impinge, and which emits a greater number of secondary electrons than impinging primary electrons, and an anode arranged to collect secondary electrons.

According to the present invention an amplifier circuit arrangement is provided comprising an electron multiplier valve, an input circuit for applying the signals to be amplified between the control electrode and cathode to the valve, an output circuit for feeding the amplified signals to an output load, an impedance in the anode-to-dynode circuit of the valve, and a negative feedback loop path from the output circuit to the input circuit and back to the output circuit, the feedback path being such that the feedback potentials are amplified by the electron multiplier valve and appear across the impedance in the anode-to-dynode circuit.

The electron multiplier valve may of course comprise more than one dynode so that more than one stage of electron multiplication occurs, the secondary electrons emitted from one dynode being caused to impinge on a successive dynode which emits further secondary electrons, electrons emitted from the final dynode being collected by the anode, and the feedback potentials may be obtained from any one of the dynodes and preferably the last dynode or from the anode of the electron multiplier valve, provided that the phase of the potentials so obtained is appropriate to afford negative feedback.

In United States Patent No. 2,431,973, issued December 2, 1947, an amplifier circuit arrangement is described for feeding electric signals, such as television signals, to a plurality of loads, such as may be constituted by reproducing apparatuses which are required to be fed from a single input source, the arrangement being such as to have a low output impedance. One application of the present invention is to an arrangement which has

2

the same function as that described in the aforesaid patent. According to this application of the present invention the arrangement comprises an electron multiplier valve, means for feeding the signals to be amplified to the control electrode-to-cathode circuit of the electron multiplier valve, an impedance in the anode-to-dynode circuit of the electron multiplier valve, a second thermionic valve having at least a thermionic cathode, a control electrode and an anode and having output terminals in part of the anode-to-cathode circuit of said second valve which is common to the control electrode-to-cathode circuit thereof, a coupling for feeding potentials from the impedance to the control electrode-to-cathode circuit of the second valve, and a feedback path for feeding at least a proportion of the potentials set up at the cathode of the second valve to the control electrode-to-cathode circuit of the electron multiplier valve in such manner as to provide negative voltage feedback from the terminals.

A single electron multiplier valve therefore takes the place of two valves having a common cathode impedance in the circuit arrangement described in the aforesaid patent where the two valves are employed in order to obtain the correct phase for a negative feedback. In addition, a greater degree of feedback is possible owing to the greater control electrode-anode slope of an electron multiplier valve compared with an ordinary valve, and the feedback gain is also doubled by avoiding the use of two cathode coupled valves. Taking both these factors into account, a feedback gain increased by about six times may be obtainable in practice using a single stage electron multiplier valve, with a corresponding improvement in the linearity of the arrangement at low frequencies, and in the upper cut-off frequency thereof.

In another application of the present invention the arrangement comprises an electron multiplier valve, means for feeding the signals to be amplified to the control electrode of the valve, an impedance connected to the cathode of the valve, output terminals connected to opposite ends of the impedance, a load impedance connected to the dynode of the valve, and a non-phase inverting coupling between the dynode and the cathode of the valve, whereby the valve is caused to operate as a cathode follower valve whose output impedance at the terminals is approximately

where g is the control electrode-to-cathode slope of the valve and x its multiplication ratio.

As will hereinafter appear an arrangement according to the present invention can also be employed to obtain a high output impedance.

In order that the said invention may be clearly understood and readily carried into effect, the same will now be more fully described with reference to the accompanying drawings wherein:

Figures 1 to 3 illustrate amplifier circuit arrangements according to different applications of the invention.

Figure 4 illustrates a modification of the arrangement illustrated in Figure 1, and

Figure 5 illustrates a modification of the arrangement illustrated in Figure 2.

Referring to the drawings, the arrangement illustrated in Figure 1 is designed to perform the same function as the arrangements described and illustrated in the aforementioned patent. Input signals are applied from a source of said signals, which may be a high impedance source, to the input terminals 1 of the arrangement, and they are repeated across the output terminals 2 in the cathode circuit of the valve 3, which is caused to operate with a very low output impedance. The load connected across the output terminals 2 may comprise a plurality of loads constituted for example by television reproducing apparatuses arranged in parallel as in the aforesaid specification. An input impedance 36 is connected between the terminals 1 and one of said terminals is connected to the control electrode 4 of an electron multiplier valve 5, the valve 5 comprising in addition to the control electrode 4, a thermionic cathode 6, a screening electrode 7, a dynode 9 and an anode 10. The anode and the screening electrode are each connected to a suitable point on a source of potential 8, the potentials applied to the anode 10 and screen electrode 7 being for example about 300 volts and 150 volts respectively.

Resistances 11 and 12 connected to a point of positive potential in the source 8 constitute a load for the dynode and the dynode is decoupled to earth by condenser 22, and potential variations developed across said load are fed to the control electrode 16 of the valve 3 by means of a coupling comprising a resistance 14 shunted by a condenser 15, the coupling being arranged to pass a wide range of frequencies as well as D. C. A leak resistance 17 is connected between the control electrode 16 of the valve 3 and a source of negative potential 18 which may vary within wide limits according to the design of the circuit and may be about 100 volts negative.

A steady potential is therefore applied to the dynode 9 which is dependent upon the value of the resistances 11, 12, 14 and 17 and upon the potential difference between the points of connection of the resistances 11 and 17 and the potential sources 8 and 18 respectively, said potential being arranged to be sufficient, say about 30 volts positive, to attract primary electrons to the dynode 9 and to provide a secondary emission ratio greater than unity from said dynode when the amplifier is first switched on. As a result, when the amplifier has been switched on there is negative current flowing in the resistances 11 and 12 to the dynode 9, and this causes the potential thereat to rise say to 200 to 250 volts. Resistance 11 is preferably made large relative to resistance 12 in order to simplify the design of the circuit for low frequency operation. The valve 3 operates as a cathode follower, the output load

being connected by means of the terminals 2 between the cathode 9 and earth.

In the arrangement shown, in order to obtain a very low output impedance at the terminals 2, a potential divider shown as comprising resistances 20 and 21 is connected between the cathode 19 of the valve and earth and a fraction of the potentials developed across the load of the valve 3 are fed back to the cathode 6 of the valve 5, the cathode 6 being connected to the junction of the resistances 20 and 21. Since the output from the valve 5 employed to drive the valve 3 is taken from the dynode 9, the valve operates as a non-phase-inverting valve, so that the potentials fed back to the cathode 6 are in correct phase to afford negative voltage feedback to the valve 5. These potentials are amplified by the valve 5 and the amplified feedback potentials are set up across the resistance 12 and thence fed to the control electrode of the valve 3. The gain of the arrangement shown is determined by the fraction of the potential across the potential divider 20, 21 which is fed back to the cathode 6 of the valve 5, and if the potential divider is replaced by a potentiometer, having the cathode 6 connected to an adjustable tapping thereon, the gain of the arrangement may be adjusted if desired.

In a modification of Figure 1 which is illustrated in Figure 4 the resistance 11 is replaced by two resistances 37 and 38 connected in series between the source of anode potential for the valve 5, and earth, the dynode 9 being connected via the resistance 12 to the junction point of the resistances 37 and 38 which point is arranged to have a sufficiently positive potential to start the operation of the arrangement on first switching on, as explained above. In addition, the condenser 22 is connected from the junction of the resistances 37 and 38 to the anode of the valve 5, so that the dynode 9 is decoupled to the anode 10, an arrangement which has the advantage that a high positive potential pulse is applied to the dynode 9 on first switching on the potential source 8 to the anode, and this may enable the steady positive potential applied to the dynode to be reduced and in some cases to be dispensed with, if the negative current flowing in resistances 37 and 38 is sufficient to maintain a suitable operating potential at the dynode when the valve is operating. This modification has also the advantage that the alternating current flowing in the source of potential for the dynode 9 and anode 10 is reduced. The remaining parts of Figure 4 are arranged in the same manner as in Figure 1.

The arrangements of Figure 1 and Figure 4 are shown D. C. coupled throughout but this may not be necessary in some applications of the arrangements.

Figure 2 illustrates an application of the invention in which the electron multiplier valve 23 is arranged to function as a cathode follower valve with a very low output impedance. The signals to be amplified are applied between the control electrode 24 and earth and the load is arranged to be connected across an impedance comprising a resistance 25, connected to the cathode and a coupling is provided by condenser 27 for feedback between the dynode 26 and the thermionic cathode 28. The dynode load is constituted by resistance 29 which is connected to earth, the thermionic cathode 28 being taken to a potential of say 300 volts negative. The anode 31 is taken to a positive potential, in the present embodiment about 300 volts, the screen electrode is

maintained at a positive potential of about 150 volts; while the control electrode 24 is arranged to have a mean D. C. potential of zero volts. The condenser shown in dotted lines at 30 is intended to indicate the total output capacity of the valve 23 including the cathode-to-ground and dynode-to-ground capacities. In addition a condenser of large capacity in relation to the condenser 27 may also be connected between the anode 31 and a tapping on the resistance 29, said additional condenser being provided to facilitate starting-up the arrangement by applying a high positive potential pulse to the dynode 26 on first switching on, as explained with reference to the condenser 22 in Figure 4.

Referring to Figure 2, let the control electrode-cathode slope of the valve 23 be g and its multiplication ratio be x , and let i_1 and i_2 be the electron currents in the branches of the circuit arrangement as shown. In addition, let the impedance of the resistances 25 and 29 and the capacity 30 in parallel be Z . Then if an input signal of e volts is applied to the control electrode 24, of sufficiently high frequency to make the reactance of condenser 27 negligibly small, and if the output signal at the cathode of the valve is v volts as indicated, the following equations can be obtained:

$$g(e-v) = i_1 \quad (1)$$

$$i_2 = i_1(x-1) \quad (2)$$

$$v = Z(i_1 + i_2) \quad (3)$$

Whence

$$i_1 + i_2 = xg(e-v)$$

and

$$v = xgZ(e-v)$$

Therefore

$$v = \frac{Z}{\frac{1}{xg} + Z} \cdot e$$

From this result it can be deduced that the output impedance of the valve 23 is approximately

$$\frac{1}{xg}$$

and provided that both the resistances 25 and 29 are large in relation to

$$\frac{1}{xg}$$

the output time constant is effectively

$$C_1 \times \frac{1}{xg}$$

where C_1 is the capacity 30. The multiplier valve connected as shown in Figure 2 therefore behaves as a cathode follower in which the effective slope is the control-electrode-anode slope of the valve. In one application of the circuit arrangement illustrated in Figure 2 in which the control electrode-cathode slope of the valve was about six and its multiplication factor about three, the value of resistance 25 is 47,000 ohms, resistance 29 was 20,000 ohms while the capacity of the condenser 27 was .01 microfarad.

In the modification of Figure 2 which is illustrated in Figure 5 the dynode 26 of the valve 23 instead of being connected to earth via resistance 29, is connected to the source of anode potential for the valve 23, said potential in this example being 300 volts positive, and a further resistance 39 is connected in parallel with the condenser 27, the arrangement being otherwise the same as in Figure 2. In one application of this modification employing a valve having a control electrode-

cathode slope of about six, and a multiplication factor of about three, the value of the resistance 25 was 12,000 ohms, resistance 29 was 40,000 ohms, resistance 39 was 12,000 ohms, while the capacity of condenser 27 was .01 microfarad. This modification has the advantages compared with the arrangement of Figure 2 of being slightly more stable and of having an improved low frequency response.

In the operation of a single stage multiplier valve it is found that as the potential applied to the dynode is increased the negative current flowing in the external circuit to the dynode increases to a maximum at a particular value of the applied potential and thereafter decreases as the potential is further increased. This is thought to be due to the fact that the increase in potential increases the ratio of the number of secondary electrons emitted from the dynode to the number of impinging electrons but at the same time causes the space charge between the dynode and the anode to become such that the number of secondary electrons collected by the anode is decreased, a greater proportion of the emitted secondary electrons returning to the dynode, and when said maximum is reached the increase in current flowing to the anode due to one effect is just balanced by the decrease in said current due to the other effect. In the circuit arrangements illustrated in Figures 1, 2, 4 and 5 of the drawings the potential maintained at the dynode of the electron multiplier valve during operation of the valve in each case is preferably near that which corresponds to said current maximum. Variation in the potential at the dynode then produces very little variation in the current flowing in the external circuit of the valve to the dynode so that the impedance at said dynode is very large.

The embodiment illustrated in Figure 3 is a further modification of the arrangement of Figure 2 in which the input signals are applied to the thermionic cathode 28 of the electron multiplier valve 23 while the output is taken from the control electrode 24 across the resistance 35, this modification taking advantage of the fact that the impedance looking into the cathode of an electron multiplier valve may be sufficiently large to employ the cathode as the input electrode. The anode 31 is coupled to the control electrode 24 by the condenser 27 and a resistance 34 in parallel with the condenser 27 to provide negative feedback to the valve 23. The anode load is constituted by resistance 32 and it is connected to a potential source of say 500 volts positive via resistance 40, the anode 31 being decoupled to said source by condenser 33 which is connected in parallel with the resistance 40, or the anode may, if desired, be decoupled to earth by the condenser 33. The circuit arrangement has similar properties to the circuit shown in Figure 2 so that its operation need not be described in detail. The potentials applied to the dynode and screen electrode are for example respectively 300 volts positive and 150 volts positive while the low potential end of resistance 35 is for example connected to a source of potential of about 30 volts negative, and the low potential end of resistance 25 is connected to a source of potential of about 300 volts negative. Resistance 40 may have the value of 10,000 ohms, resistance 32 may be 1,000 ohms, resistance 34 may be 1 megohm, resistances 25 and 35 may be respectively 12,000 and 100,000 ohms while the condenser 27 may have a capacity of .01 microfarad.

It will be understood that the invention may

be applied to other arrangements than those described above, for example, an arrangement according to the invention may be used to drive a tetrode or pentode valve, the screen electrode of which, being liable to draw current, is decoupled to the cathode, in order to present a very high impedance output to a load connected to anode of said tetrode or pentode valve, as described in the specification of U. S. patent application Serial No. 745,018. In this case the circuit would be similar to the circuit of Figure 1 of the accompanying drawing, the valve 3 being, however, replaced by a tetrode or pentode, having its screen electrode decoupled to the cathode, and arranged to have the load connected between the anode and the source of positive potential for the anode.

It will also be understood that electron multiplier valves may be employed in arrangements according to the invention having more than one dynode so as to afford further stages of electron multiplication.

What we claim is:

1. A negative feedback amplifier circuit for operation with a low output impedance, including an electron multiplier valve having at least a thermionic cathode, a control electrode, a dynode and an anode, means for feeding signals to be amplified to the control electrode-to-cathode circuit of said valve, a second valve having at least a thermionic cathode, a control electrode and an anode, a coupling from the dynode of said electron multiplier valve to the control electrode of said second valve, an output load in part of the anode-to-cathode circuit of said second valve which is common to the control electrode-to-cathode circuit thereof, and a feedback path for feeding at least a fraction of the potentials set up at the cathode of said second valve to the cathode of said electron multiplier valve to provide negative voltage feedback from said load.

2. A negative feedback amplifier according to claim 1, comprising an impedance connecting said dynode to a source of steady potential which is decoupled to the anode of said electron multiplied valve by a condenser.

3. A negative feedback amplifier circuit including an electron multiplier valve having at least a thermionic cathode, a control electrode, a dynode and an anode, means for feeding signals to be amplified to the control electrode of said valve, a resistive load impedance connected to the dynode of said valve, a second valve having at least a thermionic cathode, a control electrode and an anode, and having an output load in part of the anode-to-cathode circuit of said second valve which is common to the control electrode-to-cathode circuit thereof, a direct current coupling from said dynode to the control electrode of said second valve, and a direct current feedback path for feeding at least a portion of the potentials set up at the cathode of said second valve to the cathode of said electron multiplier valve.

10

15

30

35

40

45

50

60

4. A negative feedback amplifier circuit for operation with a high output impedance, including an electron multiplier valve having at least a thermionic cathode, a control electrode, a dynode and an anode, means for feeding signals to be amplified to the control electrode of said valve, a second valve having at least a thermionic cathode, a control electrode and an anode, a coupling from the dynode of said electron-multiplier valve to the control electrode of said second valve, an output load connected to the anode of said second valve, a feedback impedance in the cathode lead of said second valve, and a feedback path for feeding at least a fraction of the potentials set up at the cathode of said second valve to the cathode of said electron multiplier valve.

5. A negative feedback amplifier according to claim 4, wherein said second valve includes a screen electrode liable to draw current, and means for decoupling said screen electrode to the cathode of said second valve.

6. A negative feedback amplifier circuit including an electron multiplier valve having at least a thermionic cathode, a control electrode, a dynode and an anode, means for feeding signals to be amplified to the control electrode of said valve, an impedance in the cathode lead of said valve, an impedance in the dynode lead of said valve, and a coupling from the dynode to the cathode of said valve, said impedances both being large compared with the reciprocal of the control electrode-cathode mutual conductance of said valve to cause said valve to operate as a cathode follower valve whose output impedance at said terminals is approximately

$$\frac{1}{xg}$$

where g is the control electrode to cathode slope of said valve and x is its multiplication ratio.

7. A negative feedback amplifier according to claim 6, where each of said impedances includes a resistance and said coupling includes a resistance in shunt with a condenser, whereby said amplifier can transmit signals of wide frequency range and having a direct current component.
